UNITED STATES PATENT OFFICE.

ROBERT A. GOELLER, OF NEW YORK, N. Y., ASSIGNOR OF ONE-HALF TO BENJAMIN GROSS, OF NEW YORK, N. Y.

LEVER MECHANISM.

Application filed December 12, 1921. Serial No. 521,650.

To all whom it may concern:

Be it known that I, ROBERT A. GOELLER, a citizen of the United States, and a resident of New York, county of Bronx, and State of New York, have invented certain new and useful Improvements in Lever Mechanism, of which the following is a specification.

This invention relates to lever operating mechanism and more particularly to the type 10 of lever mechanism used for operating knife switches and devices of like character.

It is realized that the lever mechanism which forms the subject matter of this invention is adapted for many uses and is capable of general application, but in order to make clear one adaptation of the structure 15 the mechanism will be described as switch operating mechanism and in connection with the problem involved in such an adaptation.

Electric switches of the knife-blade type 20 require a very strong initial leverage because of the heavy initial friction to be overcome in opening. Furthermore when the knife blades are about to break contact with the terminals a rapid or quick action is 25 necessary to prevent arcing and burning of the contacts. Sometimes a spring actuated toggle mechanism is used in such switches but in such cases although the spring gives 30 the desired quick break it must be very stiff or strong to overcome the initial friction and this makes the movement of the actuating lever which compresses the spring very stiff and difficult of accomplishment.

One of the objects of this invention, therefore, is to provide lever operating mechanism that will be positive in action and easy to operate.

Another object of the invention is to provide mechanism of the character described 40 so constructed and arranged as to cause the actuated members such as knife blades to have in opening, a comparatively slow initial movement but a rapidly accelerated 45 subsequent movement.

Another object of the invention is to provide lever mechanism so constructed and arranged as to produce a comparatively great 50 initial leverage when moved in one direction and to decrease the leverage gradually as the requirements are lessened.

Another object of the invention is to provide lever mechanism so constructed and arranged as to effect upon movement in one 55 direction a great initial leverage and to

gradually decrease the leverage as the requirements decrease and further to provide a lever that will accomplish the reverse effect upon its movement in the reverse direction.

Further objects of the invention will appear from the following specification taken 60 in connection with the drawings which form a part of this application and in which—

Fig. 1 is a top plan view of the invention as applied to a multi-pole switch.

Fig. 2 is a sectional elevation taken substantially on line 2—2 of Fig. 1.

Fig. 3 is an end elevation of the construction shown in Figs. 1 and 2, portions of the switch being broken away to more clearly 70 show the remaining parts.

Fig. 4 is a diagrammatic view of the switch shown in Figs. 1-3 with the parts shown in switch open position and

Fig. 5 is an elevation, more or less diagrammatic, showing a simpler form of switch having my invention embodied 75 therein.

The invention may be briefly described as comprising a frame having an actuating 80 member pivoted thereon, an actuated member pivoted thereon on a pivot spaced from the pivot of the first member and means such as a link pivoted to and connecting said members, the pivots being so located that the initial movement of the actuating member will cause a comparatively slow and comparatively small initial movement of the actuated member from one extreme position but the further and subsequent movement of the actuating member will cause a comparatively large and a comparatively rapid movement 85 of the actuated member.

In the particular embodiment of the invention illustrated, as above stated, the lever mechanism has been shown in connection 90 with multi-pole knife switch actuating mechanism and in Figs. 1-4 inclusive, a toggle switch is illustrated and in Fig. 5 a simple, manually operated switch is illustrated.

Referring first to Figs. 1-4, the frame of the switch is shown at 10 and has legs 11 adapted to be secured to a support and laterally extending lugs 12 adapted to receive securing means for the cover or casing (not shown).

The actuating lever 13 is pivoted at 14 to the frame and has a handle 15 by means of which it may be operated. The lever also 110

has a pair of laterally extending lugs 16 which project into slots 17 formed in the frame and limit the throw of the operating lever.

6 The lower end of the operating lever is slotted as shown at 18 and has a bridge portion 19 between the slot and an opening 20 in the lever. This bridge portion receives a forked or bifurcated end 21 of a rod 22, the 10 opposite end of which extends through an opening or slot 23 formed in the bottom or cross portion 24 of a saddle member 25, the latter being pivoted at 26 to the frame 10. A spring 27 surrounds the rod 22 and is positioned between the part 24 and a washer 27' at the forked end 21 of the rod.

20 The portion 24 of the saddle member has formed thereon an extension 28 to which is pivoted at 29 a link 30. The opposite end 25 of this link is pivoted at 31 to a member 32 which may be termed a knife blade carrier and to which are secured on insulated posts, as shown at 33, the knife blades 34. The carrier 32 is pivoted at 35 to the frame 10. The portions 24 and 28 of the saddle member 25 engage stops 24' and 28' formed by the frame 10 thereby limiting the throw of the saddle member.

30 The operation of the construction shown in Figs. 1-4 inclusive, will now be briefly outlined. As illustrated particularly in Fig. 2, it will be noted that the pivots 26, 29 and 31 in the closed position of the switch are substantially aligned and that the link 30 is 35 disposed substantially at right angles to the blade carrier and knife blades. As will, of course, be understood the initial movement of the toggle lever 13 compresses the spring 27 and this compression is continued until 40 the spring rod 22 is thrown over dead center whereupon the spring will actuate the saddle 25 and will cause the blades to disengage from the contact terminals. Because of the peculiar arrangement and relative locations of the pivots 26, 29 and 35, the initial 45 movement of the saddle will cause a very slow movement of the knife blades, with but slight acceleration, until they are released from their coengaging contact terminals. 50 This relative location of the pivots also results in a comparatively great leverage to overcome the friction between the blades and the contact members. When, however, the blades are freed from the contacts or are 55 about to be freed, the further movement of the saddle will cause a rapid acceleration of the blades thereby preventing arcing or burning of the blades and terminal contacts. From the showing in Fig. 4 the final 60 positions of the respective pivots and actuating and actuated parts may be understood. It will be noted that the pivot 29 has moved to a position much closer to the pivot 35 than its initial position and because of this fact 65 the leverage has been decreased. The opera-

tion is such therefore that the greatest leverage is realized at the initial movement of the mechanism and of the knife blades when, of course, the greatest leverage is required. After the blades are freed from their contacts the leverage is gradually decreased but the rate of movement of the blades is increased.

Without explaining in detail the reverse movement of the lever mechanism, it will be understood that the initial return movement will be rapid and that the leverage will increase and the rate of movement of the parts will be decreased as the switch is closed. Thus a high leverage will be obtained as the friction increases due to the engagement of a greater area of the contacts by the knife blades.

In Fig. 5 is illustrated a simpler embodiment of the invention and in this embodiment the spring toggle mechanism is not utilized. A lever 250 corresponds to the saddle 25 in Fig. 2 but this lever is provided with an extension 251 beyond its pivot 260 at which point it is pivoted on the frame 10. A link 300 is pivoted at 290 to the lever 250 and is pivoted at 310 to the knife blade carrier or the knife blade 320. The part 320 is pivoted at 350 to the frame 10.

The operation of the device shown in Fig. 5 is slightly less involved than that in the construction shown in Figs. 1-3 but the similarity between the two constructions will be obvious when it is borne in mind that instead of actuating the saddle 25 as shown in Fig. 3 by means of spring toggle mechanism, the corresponding member 250 in Fig. 5 is extended beyond its pivot and is directly operated. When the extension 251 of the lever 250 is swung on its pivot 260 the initial movement of this lever will cause the link to swing from the substantially vertical position about its pivot 310. This will cause a slow movement of the knife carrier 320 and a comparatively large leverage will be obtained. When the blades or blade carrier 320 has moved through a sufficient angle to clear the co-engaging contact members the link 300 which has been swinging from the vertical toward the horizontal position will exert a more direct pull on the carrier 320 and will cause this carrier to move at a rapid rate. As was the case with the construction shown in Figs. 1-4, the pivot 290 in the position assumed when the parts are in the fully opened position is located much closer to the pivot 350 than in the initial positions of these pivots. The leverage is therefore decreased and the relative speeds of the actuating and actuated members have increased.

Another result of the operation of the switch blades in the manner described, namely a relatively slow, initial opening movement followed by a rapidly accelerat-

ing movement as the blades break contact, may be briefly outlined as follows.

With the ordinary "quick break" switch the period of breaking of the circuit is very short due to the fact that the blades attain their maximum rate of speed substantially at the start of their opening movement, causing a violent line fluctuation due to the extremely rapid change in resistance between the circuit breaking members.

However with the construction described in the foregoing specification, the relatively slow initial movement of the blades followed by the rapidly accelerating movement tends to overcome this difficulty and effect a minimum line fluctuation due to the more gradual change in resistance between the circuit breaking members.

As stated at the outset of this specification although the lever operating mechanism has been shown particularly in connection with an electric switch of the multi-pole type, it will be understood that the mechanism and the mechanical movement by means of which the results are accomplished are capable of general application and are not limited to the particular form of the invention shown. Moreover, where horizontal or vertical positions are mentioned they are so shown and described merely as matter of convenience.

Furthermore, although certain specific embodiments of the invention have been illustrated and described, it will be understood that the invention is capable of further modification and that further changes in the construction and in the arrangement of the various cooperating parts may be made without departing from the spirit or scope of the invention as expressed in the following claims.

What I claim is:

1. In combination, a frame, a member pivoted thereon, toggle means for swinging said member on its pivot, a second member pivoted on said frame on a pivot spaced from the pivot of the first mentioned member and a link pivoted to both of said members, the link pivots and pivot of the first member being substantially alined in their initial positions.

2. A switch comprising a frame, a member pivoted thereon, toggle means including a spring for swinging said member on its pivot, a blade pivoted on said frame on a pivot spaced from the pivot of the first mentioned member, and a link pivoted to said member and said blade.

3. A switch comprising a frame, a lever pivoted thereon, a saddle pivoted on said frame, a toggle connection including a spring between the lever and the saddle, blade carrying means pivoted on said frame and a link pivoted to said saddle and to said blade carrying means.

4. A switch comprising a frame, a lever pivoted thereon, a saddle pivoted on said frame, a toggle connection including a spring between the lever and the saddle, blade carrying means pivoted on said frame and a link pivoted to said saddle and to said blade carrying means, said saddle pivot and link pivots being disposed in substantial alinement when the parts are in switch closing position.

5. A switch comprising a frame, a lever pivoted thereon, a saddle pivoted on said frame, a toggle connection including a spring between the lever and the saddle, blade carrying means pivoted on said frame and a link pivoted to said saddle and to said blade carrying means, said link being disposed at an angle to a line intersecting the pivots of the blade carrying means and saddle when the parts are in switch closing position.

6. A knife switch comprising a frame, an actuating lever pivoted thereon, an actuated member pivoted on the frame, knife blades carried thereby, and a link connecting said actuating member and actuated member, the pivots of said actuated and actuating members on the frame and the link pivotal connections to said members being so constructed and arranged that the initial closing movement of the actuating member will effect a relatively faster movement of the actuated member and blades and further closing movement of the actuating member, as the blades engage their contacts, will effect a movement of the actuated member and blades under an increasing leverage at a decreased rate with respect to the rate of movement of the actuating member, and the initial opening movement of the blades will be relatively slow and under relatively great leverage and the further opening movement will be accelerated with a decreasing leverage.

7. A knife switch comprising a frame, a lever pivoted thereon, a knife carrying member pivoted on the frame, a link connecting said lever and said member and spring toggle mechanism pivoted on the frame and connected to actuate the lever, the parts being so constructed and arranged that initial movement of the toggle mechanism in either direction will compress the spring.

8. A switch comprising a frame, a hand lever pivoted thereon, a saddle lever pivoted on the frame on a pivot disposed below the lever pivot, a compressible, resilient connection between the lower portion of said hand lever and the saddle lever, a knife carrier pivoted on the frame on a pivot laterally spaced from the saddle lever pivot and a link pivoted to the carrier and to the saddle lever.

9. A switch comprising a frame, a hand lever pivoted thereon, a saddle lever pivoted

on the frame on a pivot disposed below the lever pivot, a compressible, resilient connection between the lower portion of said hand lever and the saddle lever, a knife carrier 5 pivoted on the frame on a pivot laterally spaced from the saddle lever pivot and a link pivoted to the carrier and to the saddle lever, the link pivots and saddle lever pivot being disposed in alinement when the switch 10 is in closed position.

10. A switch comprising a frame, a hand lever pivoted thereon, a saddle lever pivoted on the frame on a pivot disposed below the hand lever pivot, a compressible, resilient 15 connection between the lower portion of said hand lever and the saddle lever, a knife carrier pivoted on the frame on a pivot laterally spaced from the saddle lever pivot and a link pivoted to the carrier and to the 20 saddle lever, the link pivots and saddle lever pivot being disposed in alinement with the switch when it is in closed position, the hand lever, saddle lever and resilient connection being so relatively located and arranged that 25 initial movement of the hand lever in either direction compresses the spring.

11. A knife switch comprising a frame, spring toggle mechanism thereon, a manually operable lever for setting said spring toggle mechanism in operation, knife blades 30 and means connecting said spring toggle mechanism, and blades, operable upon the actuation of and by the spring toggle mechanism, to open or close the switch, said connecting means being constructed and arranged to give a heavy initial opening leverage and a heavy final closing leverage.

12. A knife switch comprising a frame, spring toggle mechanism thereon, a manually operable lever for setting said spring 40 toggle mechanism in operation, knife blades and link means connecting said spring toggle mechanism and blades, operable upon the actuation of and by the spring toggle mechanism, to open or close the switch said connecting means being constructed and arranged to give a heavy initial opening leverage and a heavy final closing leverage.

In witness whereof, I have hereunto set my hand this 10th day of December, 1921.

ROBERT A. GOELLER.
